FOLDING BED CONSTRUCTION

Original Filed June 9, 1926

Fig. 1.

UNITED STATES PATENT OFFICE

ALEXANDER C. BEECH, OF NAPERVILLE, ILLINOIS, ASSIGNOR TO KROEHLER MANUFACTURING COMPANY, OF NAPERVILLE, ILLINOIS, A CORPORATION OF ILLINOIS

FOLDING-BED CONSTRUCTION

Application filed June 9, 1926, Serial No. 114,631. Renewed November 14, 1929.

This invention relates to a folding metal construction adapted to be used either for a davenport or a day bed.

Among the objects of this invention are: 5 To provide a two-section construction of this kind in which the sections are movable from a position one above the other to a position in alignment and at the height of the upper section in its folded condition; to provide extensible means for supporting the sections in extended and folded position, thereby eliminating any slotted connection with the frames; to simplify the arrangement and disposition of the parts so that the bed sections 10 may be readily folded and unfolded; and in general to produce the construction herein shown and described.

In the accompanying drawings:

Figure 1 is a side elevation with parts 20 shown in section of a folding bed construction, in accordance with the principles of this invention, as applied to a davenport, and in extended position;

Figure 2 is a plan view of one end of the 25 structure as shown in Figure 1; and

Figure 3 is a sectional side elevation of the structure in folded position.

Referring more particularly to the drawings, the numeral 1 generally designates an 30 end frame of a day bed or davenport having front and back cross pieces 2 and 3 connecting the opposite end frames and in the case of a davenport an upholstered back 4 is also secured in place between the end frames 1. The 35 structure thus described is commonly made by furniture manufacturers in various forms and styles, upholstered or not as desired, and a metal folding bed construction separately produced and assembled as a unit is applicable to the frame. This metal folding construction comprises a pair of cross pieces 5 provided with front and rear uprights 6 and 7 attached to the end of each cross piece, and the upright forming means for attaching the 45 cross pieces to the end frame and the connecting rails.

The lower or rear bed frame section 8 is mounted to swing on parallel levers 9 which in turn are pivoted on the cross piece 5 and 50 swing the frame 8 upwardly and forwardly

until a stop 10 projecting from the cross piece is engaged by one of the levers 9.

An upper or front bed section 11 is pivotally mounted adjacent the rear side thereof upon a rigid lever 12 and an extensible link 13 both of which have fixed pivotal connections not only with the frame section 11 but also with the cross piece 5. The front lever 12 engages a shoulder on the front upright 6 for limiting the movement of this lever and 10 pivotally connected adjacent the upper end of the lever is a link 14 which operates a folding leg 15 to support the front side of the section 11 when it is extended. At the outer edge of the front section 11 is a movable front 15 board 16 which rests upon the fixed front board 2 for supporting the section in its folded position, as shown in Figure 3.

The extensible link 13 for the inner end of the bed section 11 comprises telescoping 20 parts 17 and 18 pivoted to the bed section 11, and the cross piece 5, fitting closely, but freely slidable one within the other. Closely surrounding these telescoping members is a tension spring 19, the ends of which are attached to the telescoping members 17 and 18 adjacent their pivotal points, as for example by inserting the ends through suitable apertures in the telescoping members, and this spring tends to force the members in telescoping relation.

In order to move the rear section 8 in accordance with the movement of the front section 11, a bracket 20 is affixed to and depends from the frame 11 adjacent its inner side at 25 each end thereof, and connecting each bracket with the rear section 8 are two pivotally connected links 21 and 22 and the upper edge of the link 21 engaging the under side of the section 11 for supporting it in alignment with section 8 and holding the extensible link 13 in distended position, the free end of the latter being pivotally connected at the end of the frame 8 to a fixed pivot 23, and the under side of this link 22 being engaged by a projection 24 extending from the frame of section 8 to limit the downward movement of this link 22.

At the rear of each cross piece 5 is an upright 25 supporting a horizontal piece 26 100

which is adapted to engage the front section 11 in its folded position and to form a sliding conductor for the rear side of the front or upper section 11. Extending inwardly from the lower edge of the cross piece 5 are supporting brackets 27 for engaging the rear bed section 8 in its lower or folded position, as shown in Figure 3.

The folding and unfolding action of this construction is very simple, and assuming the bed to be closed, as shown in Figure 3, the front edge of the upper section is grasped and raised upwardly, swinging it upon the levers 12, the rear of this section resting and sliding upon the supports 26, and the telescoping lever 13 giving slightly under this movement but holding the rear side of the section against the rear supports 26. The forward movement of the section 11 will cause the connected links 21 and 22 first to swing downwardly at their pointed end, and then as the outward swinging movement of the front section 11 is continued these links 21 and 22 are extended until they are in a straight line, and the continued movement of the front section 11 will raise the rear section 8 upon its parallel levers 9 until the rear section is in its elevated position with one of the levers 9 against the stop 10 at which time the front section 11 will be in its forward or unfolded position with its supporting legs 15 automatically extended and upholding the front edge. At this time the connected links 21 and 22 which are slightly out of alignment would tend to have their common pivot fall were it not for the engagement of link 22 with the stop or projection 24 which holds these links out of alignment ready for the folding movement of the sections.

In the folding action, the operations are substantially reversed, the raising movement of the outer section 11 swinging the rear section 8 downwardly because of the direct connection of the links 21 and 22, and the extensible lever 13 tends to draw down the rear side of the front section 11 to engage the rear supports 26 so that the rear side of the front and section slides upon the rear supports 26 and swings rearwardly upon the fixed levers 12 until the front board 16 engages the fixed front board 2.

With this construction it is obvious that the action in folding and unfolding not only is simple but also requires little strength so that the construction is easily folded and unfolded by women and children, as the front section is swung easily about the levers 12, the rear resting upon the supports 26 and sliding forwardly thereon, and the weight of the rear section is not applied until the front section is at or over its center of gravity tending to fall forward on the levers 12 which helps to balance the weight of the rear sections 8 in raising it. In the closing action the first upward movement of the front sec-

tion 11 tends to swing the rear section backwardly upon its parallel levers 9 so that the weight of the rear section partially counterbalances the weight of the front section in the closing action. The extensible telescoping lever 13 makes it possible to swing the outer, section 11 more freely; it holds down the inner side of the section 11 in both extended and folded positions; and it permits the sliding action of the inner end of this section upon the inner fixed supports so that the section will slide more readily under the projection such as an upholstered back 4, thereby making it possible to provide a close fit or construction between the back and the seat, which is desirable in davenport constructions.

I claim:

1. In a folding bed construction, a pair of bed sections movable from a position one over the other to a position in alignment with each other, means for swinging the upper section forwardly and drawing the lower section upwardly, said swinging means including a pair of members at each end of the sections, one of which is a resilient extensible telescopic link. 90

2. A folding bed construction having upper and lower bed sections movable into alignment, means for raising the lower section when the front section is moved, and means for swinging the front section forwardly, said means including resilient telescoping extensible members. 95

3. A construction in accordance with claim 2 in which the telescoping extensible members have a surrounding spring tending to draw the members together. 100

4. In a folding bed structure, upper and lower sections movable into alignment, means for mounting the lower section to swing upwardly, means for mounting the upper section to swing forwardly without overturning, and means comprising a double link connection between the sections at each end thereof for positively raising the rear section when the front section is moved forwardly, one of said links at each end engaging the rear edge of the front section to hold the sections in alignment. 105

5. In a folding bed construction, upper and lower bed sections, a pair of members for swinging the lower section upwardly, a pair of members for swinging the upper section forwardly, one of the last mentioned members being extensible, means connecting the sections for raising the lower section when the upper section is moved forwardly, a rear support for the upper section in its folded position, the extensible means being provided with a spring for retaining the rear side of the upper section in engagement with the said support so that the upper section will slide forwardly and rearwardly on the said support in the folding and unfolding movements of the upper section. 120

6. In a folding bed construction, a pair of 130

bed sections, means for mounting the sections to swing from a position one above the other to a position in alignment with each other, and a jointed connection between the sections 5 engageable with a projection from the lower section and engaging below the adjacent edge of the upper section for holding the sections in alignment.

7. In a folding bed construction, a pair of 10 bed sections, means for mounting the sections to move from a position one above the other to a position in alignment with each other, and a connection between the sections comprising a double link pivoted at the end of the 15 lower section and to the under side of the upper section, and a projection extending from the lower section adapted to engage the link pivoted thereto for holding the other link in position below the adjacent edge of the other 20 section for maintaining the sections in alignment.

8. In a folding bed construction, a pair of bed sections movable from a position one over the other to a position in horizontal alignment 25 with each other, means for swinging the upper section forwardly and drawing the lower section upwardly, said swinging means for the upper section comprising a pair of links at each end of the section, one of which 30 is a rigid link and the other of which is a resilient extensible link whereby this section may be independently rocked about a horizontal axis formed by the pivots of the rigid links.

35 9. In a folding bed structure, upper and lower sections movable into alignment, means for mounting the lower section to swing upwardly, means for mounting the upper section to swing forwardly without overturning, 40 means comprising a double link connection between the sections at each end thereof for positively raising the rear section when the front section is moved forwardly, one of said links at each end engaging the rear edge of 45 the front section to hold the sections in alignment, and means including a projection at each end of the lower section for engaging the other of the said links for limiting the downward movement thereof.

ALEXANDER C. BEECH.
